UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed January 18, 1918, Serial No. 212,461. Renewed August 28, 1920. Serial No. 406,731.

To all whom it may concern:

Be it known that I, EDGAR D. JOHNSON, a citizen of the United States, residing at East Orange, in the county of Essex, State of New Jersey, have invented certain new and useful Improvements in Signaling Systems, of which the following is a full, clear, concise, and exact description.

This invention relates to electric circuits 10 wherein a repeater or the like is connected between two transmission line sections in one manner for transmission in one direction and in another manner for transmission in the opposite direction.

15 An object of the invention is to effect reversal of the repeater connections automatically, in response to current, such as voice current, impressed on the lines.

The invention in one of its aspects provides a single repeating unit which is normally connected between the two terminals 20 of a telephone line for transmission in one direction, a reversing switch being provided between each line section and the transmitter. A voice relay is connected in series 25 to each of the lines, and the operation of either of the voice-operated relays serves to render the other inoperative, and changes the connections of the repeater to the line 30 terminals in case it is necessary that such change be made for transmission of current in the proper direction. Upon the cessation of voice current in the telephone line, the repeater remains normally connected to 35 transmit current in one direction through the telephone lines. Further objects of the invention will be made apparent in the following detailed description taken in connection with the accompanying drawing, in 40 which the single figure shows diagrammatically a two-way repeating system which illustrates the invention.

Referring to the drawing, the repeater 1, which is here shown as of the mechanical 45 type, but any other type may be employed, is adapted to be reversibly connected between the lines 2 and 3 by means of the electromagnetic switches 4 and 5. The switches 4 and 5 are controlled by the direct current 50 relays 6 and 7, and the latter are in turn controlled by the voice relays 8 and 9. The invention is not limited to any particular form of voice-operated relay, and as illustrating one type of relay that may be employed, reference is made to the patent to 55

Brown, No. 1,185,472, telephony, May 13, 1916. The voice-operated relays 8 and 9 are responsive to alternating or pulsating current, such as voice current, to cause the vibration of the normally closed contacts 10 and 11, respectively.

With the connections shown in the drawings, the repeater is adapted to transmit current in the direction from the line 2 to the line 3, by way of the following circuits: 65 from line 2, armature 12 of switch 4 (this switch being deenergized), input coil 13 of the repeater 1, armature 14 of switch 4, voice relay 8 to line 2. Current in the output side of the repeater 1 passes by way 70 of the repeating coil 15 through armatures 16 and 17 of switch 5, to the line 3, the voice relay 9 being short-circuited by armature 18 of relay 19, by reason of the fact that the voice relay 8 has previously vibrated its 75 contacts 10 to sufficiently deenergize switch 19, so that the armature 18 assumes its closed position. With current approaching the repeater 1 by way of the line 2, the only 80 change in the connections shown is the short-circuiting of the relay 9 which renders the same inoperative.

If current approaches the repeater 1, connected as shown, by way of the line 3, it is necessary that the switches 4 and 5 be 85 operated to reverse the connections of the repeater between the lines, so that the input side of the repeater is connected to the line 3, and its output side to the line 2. It is also necessary that the voice relay 8 should 90 be rendered inoperative. These changes in the conditions of the circuit are brought about in the following way: When no current is coming in over either line 2 or line 3, the contacts 10 and 11 are quiet, and the 95 relay 19 and similar relay 20 are energized, thereby attracting their armatures 18 and 21, respectively, which effectively connects the relays 8 and 9 in series in their corresponding lines. Current coming in over line 3 passes through armature 16, secondary of repeating coil 15, armature 17, voice relay 9 to the line 3. The voice relay 9 being energized, its contact 11 is vibrated, thereby deenergizing relay 20 and shunting the relay 8 by means of the armature 21. The vibration of contact 11 also serves to deenergize the relay 6, and the circuit may be traced from ground, through armature 11, armature 22 of relay 7, winding of 110

May 22, 1923.

E. D. JOHNSON

SIGNALING SYSTEM

Original Filed Jan. 18. 1918

Inventor:
Edgar D. Johnson
by J. E. Roberts Atty.

- mechanism therefor and means for controlling said switching mechanism comprising a plurality of relays, contacts controlled thereby, and auxiliary switching mechanism, 5 said relays being responsive to current impressed on said line for alternately connecting said contacts to control said auxiliary switching mechanism.
7. The combination of two lines, a repeater to be reversibly connected thereto and means for controlling the repeater connection, comprising a plurality of the following elements: a relay, a contact controlled thereby, a second relay controlled by 10 said contact, and means responsive to the actuation of said contact to change its controlling relation with respect to said second relay; one of said first-mentioned relays being responsive to current impressed on one 15 of said lines, another thereof being responsive to current impressed on the other line.
8. The combination of two lines, a repeater to be reversibly connected thereto and means for controlling the repeater connection, comprising a plurality of the following elements: an A. C. relay, a normally 20 closed vibratile contact controlled thereby, a second relay controlled by said contact, and means responsive to the actuation of 25 said contact to change its controlling relation with respect to said second relay; one of said A. C. relays being responsive to current impressed on one of said lines, and another thereof being responsive to current 30 impressed on the other line.
9. The combination of two lines, a repeater to be reversibly connected thereto and means for controlling the repeater connection, comprising a plurality of the following elements: an A. C. relay, a normally closed 35 vibratile contact controlled thereby, a second relay controlled by said contact, and means responsive to the actuation of said contact to disconnect it from the winding of said second relay; one of said A. C. relays being responsive to current impressed on one of 40 said lines, and another thereof being responsive to current impressed on the other line.
- 50 10. The combination of two telephone lines, a repeater therefor, switching means having a bias constant in direction connected between said repeater and each of said lines, and an alternating current relay in series with each of said lines and common to said switching means.
11. Two telephone lines, a repeater therefor, a switch having a bias constant in direction connected between each line and 55 said repeater, a solenoid for each of said switches, an alternating current relay in series with each of said lines, a vibratile contact for each of said relays, and connections whereby said solenoids are controlled by one of said relays.
12. Two telephone lines, a repeater therefor, a switch between each line and said repeater, a solenoid for each of said switches, an alternating current relay in series with each of said lines, a vibratile contact for each of said relays, and connections whereby both of said solenoids are controlled by each of said relays. 70
13. The combination of two telephone lines, a repeater therefor, switching means having a bias constant in direction for reversibly connecting said repeater to said lines, said switching means comprising a plurality of solenoids, and an alternating current relay in series with one of said 75 lines for controlling said solenoids.
14. A repeating system comprising two lines, a unidirectional repeater, reversing switching means having a bias constant in direction for connecting said repeater for two-way transmission between said lines, said repeater being connected for transmission in one direction between said lines in the absence of current to be repeated, and means, including a voice relay in series 80 with one of said lines, for controlling the reversal of said repeater.
15. A repeating system comprising two lines, a unidirectional repeater, reversing switching means for connecting said repeater for two-way transmission between said lines, said repeater being connected for transmission in one direction between said lines in the absence of current to be repeated, and means for controlling the reversal of said repeater, said last mentioned means including voice relays one of which is in series with one of said lines and one of which renders another ineffective at times. 85
16. A repeater system comprising a line, a repeater therefor, a voice operated relay associated therewith, a circuit in shunt to said relay for controlling the operation thereof, and means responsive to current impressed on said line for controlling said 90 shunt circuit.
17. A signaling system comprising a repeater, a line, and means for reversibly connecting said repeater thereto, said means including two sets of relatively movable contacts connected in tandem, a winding responsive to alternating voltage on said line for operating one of said sets, and electromagnetic means controlled by said one set for controlling said other set. 95
18. A signaling system comprising a repeater, a line, and means for reversibly connecting said repeater thereto, said means including two sets of relatively movable contacts connected in tandem, a winding for holding one of said sets open, a winding responsive to alternating voltage on said line for operating the other of said sets, and a relay controlled by said other set for controlling said first mentioned winding. 100
- 105
- 110
- 115
- 120
- 125
- 130

19. The combination of a line, a relay therefor, a contact controlled by said relay, a second relay controlled by said contact, and means responsive to the actuation of said second relay to change the controlling relation of said contact with respect to said second relay.
20. The combination of a line, an alternating current relay responsive to current impressed on said line, a normally closed vibratile contact controlled by said relay, a second relay controlled by said contact, and means responsive to the actuation of said contact to change its controlling relation with respect to said second relay.
21. A two-way repeater system comprising a line, a repeater adapted to be reversibly connected thereto, switching mechanism between said line and said repeater, a relay responsive to current in said line for controlling said mechanism, a contact controlled by said relay, a second relay controlled by said contact, and means responsive to actuation of said second relay to change the controlling relation of said contact with respect to said second relay.
22. The combination of a line, an alternating current relay responsive to current impressed on said line, a normally closed vibratile contact controlled by said relay, a second relay controlled by said contact, and means responsive to the actuation of said contact to disconnect it from the solenoid of said second relay.

In witness whereof, I hereunto subscribe my name this 14th day of January A. D. 1918.

EDGAR D. JOHNSON.
